UNITED STATES PATENT OFFICE.

FRANKLIN P. BURNHAM, OF MIDDLETOWN, OHIO.

DESIGN FOR A BICYCLE-FRAME.

SPECIFICATION forming part of Design No. 26,588, dated February 2, 1897.

Application filed November 9, 1896. Serial No. 611,566. Term of patent 7 years.

To all whom it may concern:

Be it known that I, FRANKLIN P. BURNHAM, a citizen of the United States, residing at Middletown, in the county of Butler and State of Ohio, have invented a certain new and useful 5 Design for Bicycle-Frames, of which the following is a description.

My invention relates to a design for bicycle-frames, and has for its object to provide 10 the new and improved design illustrated in the accompanying drawing.

The drawing shows a view of the frame 15 separate from the other parts of the bicycle. Said frame is composed of the pieces A, B, C, and D, the bifurcated bar or piece having the end E' and the members E E, the ends of said bifurcated bar or piece connected to the frame by means of rods F F. The part D is provided at its lower end with two curved

branches E² and E⁴, the branches E² connected 20 with the part E' and the branches E⁴ with the part E³, thus forming a three-sided or triangular figure at the base of the part D, the sides E² and E⁴ of the triangular-shaped figure being curved instead of straight, while the 25 base presents a relatively straight line.

The essential feature of my design is the frame provided with the part D, which is divided at its bottom into the two curved branches, which are connected to the remainder 30 of the frame in the manner shown.

I claim—

The design for a bicycle-frame substantially as shown and described.

FRANKLIN P. BURNHAM.
